VENETIAN BLIND

Edgar Gill Ewing, New Orleans, La.

Application December 6, 1945, Serial No. 633,174

5 Claims. (Cl. 160—115)

1

This invention relates to a Venetian blind. More specifically it relates to a Venetian blind in which the slats are arbitrarily divided into upper and lower sections which sections are relatively adjustable to open or closed positions.

In Venetian blinds as at present constructed, all of the slats are simultaneously adjustable by tilt-cords. Operation of these cords causes all of the slats to be simultaneously moved to open, partially open, or closed position. There are times, however, when it is desirable to have the lower section of the slats closed while the upper section remains open and vice versa. For instance, in the late morning or early afternoon it may be desirable to close out the brilliant sun-light through the upper sash of the window while maintaining light and ventilation through the lower sash; conversely, one lying in bed or dressing may desire not to be exposed to exterior view through the lower sash while at the same time to have light and ventilation through the upper sash.

It is therefore an object of the present invention to provide a Venetian blind in which the slats of the upper and lower sections are relatively adjustable.

Another object of the present invention is to provide a Venetian blind adjustable in sections in which the sectional adjustment means can be used in conjunction with the conventional elevating and adjusting mechanisms for the entire blind without any modification of the former and with only slight modification of the latter.

A corollary object of the present invention is to provide an operating device particularly adapted for use in conjunction with the sectional tilting means of the invention.

Still other objects and advantages of the invention will become apparent from reading of the following description in connection with the accompanying drawings in which:

Fig. 1 is a side elevation view of a Venetian blind embodying the present invention;

Fig. 2 is a sectional view taken on the section line 2—2 of Fig. 1 showing the elevating cords, latter tapes for tilting the slats, and the sectional tilting cords of the present invention;

Fig. 3 is an end elevation view showing the upper section of the slats in open position and the lower section in partially closed position by the sectional tilting cords of the present invention;

Fig. 4 is a view similar to Fig. 3, but showing the lower section of the slats in open position and the upper section in partially closed position;

2

Fig. 5 is a view similar to Fig. 3, but showing a modified operating device for the sectional tilting means of the present invention mounted on the head casing; and,

Fig. 6 is a side elevation view of the structure shown in Fig. 5.

Referring now to the drawings and to Fig. 1 in particular, the ordinary Venetian blind is supported from a head casing 10, which casing encloses the elevating and tilting mechanisms. The head casing consists of a top plate 11, side plates 12—12, end plates 13—13, and a bottom plate 14, all secured together in any suitable manner as by screws (not shown) or spot welding. 15 The blind itself consists of a plurality of vertically spaced slats 19 spaced apart a distance approximately equal to the width of the slats. A bottom rail 20 is positioned in parallel relationship with the lowermost slat 19. The slats 19 and the bottom rail 20 are supported by ladder tapes 21—24. Preferably the ladder tapes 21—21 are looped web members with the sides of each loop extending downwardly along the outside and inside edges, respectively, of the slats 19 and the 25 end of the sides being attached to the bottom rail 20 in any suitable manner, as by stapling. The individual slats 19 are supported on "rungs" or cross webs 22 which are secured at their ends in any suitable manner, as by stitching, to the sides of the ladder tapes 21—21. It is conventional in the art to position one butt end of each cross web member 22 directed upwardly, and the opposite butt end directed downwardly. The ladder tapes 21—24 prevent the slats 19 from being shifted transversely and the cross webs 22 both support the slats and transmit motion thereto from the ladder tapes for tilting the slats, as will be later described.

The ladder tapes 21—24 pass upwardly 40 through suitable apertures 15 in the bottom plate 14 of the head casing 10, and the looped upper ends of these tapes pass arcuately over longitudinally spaced drums 23—23 inside the head casing 10, the tapes being secured to the drums along the arcs of contact in any suitable manner. If the drums are made of wood, the tapes may be secured thereto by tacking. The drums 23—23 are mounted on a longitudinally extending shaft 24 which is journaled in hangers 25—25, these hangers being mounted on the bottom plate 14 of the head casing 10 in any suitable manner, as by bolts or screws (not shown). At the left end, as shown in Fig. 1, a worm wheel 26 is mounted on the shaft 24. A worm gear 27 is in mesh with the worm wheel 26, the latter being mounted on, or formed in-

tegrally with, a shaft 28 which is journalled transversely of the head casing 10 in suitable bearing means (not shown). Mounted on the shaft 28 is a pulley 29. A continuous cord 30—31 is attached in any suitable manner at its upper loop to the pulley 29, as by a spring clip (not shown) and this cord extends downwardly through a suitable aperture in the bottom plate 14 of the head casing 10.

It will readily be seen that by pulling on the cord 30, pulley 29, shaft 28, worm gear 27, worm wheel 26, shaft 24, and drums 23—23 will be rotated to lift the inner side of the ladder tapes 21—21 to tilt the slats 19 from the open position of Fig. 1, to closed position. Conversely, by pulling on the cord 31 the components of this mechanism will be rotated in the opposite direction and the outer side of the ladder tapes 21—21 will be raised and the inner sides of these ladder tapes lowered to shift the slats 19 from the closed back to the open position of Fig. 1. It is well known in the art to provide friction braking means for the pulley 29, shaft 28, or shaft 24, so that the slats 19 will remain in the set position until it is again desired to shift the same. However, it is also well known in the machine art that, if the threads on a worm wheel and a worm gear are cut at a certain pitch, the worm wheel will not transmit motion to the worm gear.

The above described tilting mechanism for the entire slat structure forms no part of the present invention and for this reason several details of the same have been omitted.

The elevating cords 32—33 are the sides of a single looped cord. These cords pass downwardly through centrally positioned apertures 34—34 in the slats 19 and the bottom rail 20, the cord 32 being aligned centrally, as shown in Fig. 1, with the left ladder tape 21 and the cord 33 being aligned centrally with the right ladder tape 21. These cords terminate in knots 35 in countersunk recesses 36 in the bottom rail 20. The cords pass through the same apertures 15—15 in the bottom plate 14 of the head casing 10, and thence over pulleys 37 aligned transversely with the ladder tapes 21—21, respectively. The pulleys 37—37 are journalled on shafts 38 which are mounted on brackets 39, the latter being secured to the bottom plate 14 of the head casing in any suitable manner, as by bolts or screws (not shown). At the right end (Fig. 1) of the head casing 10 both cords pass over a third pulley 37, and thence downwardly through an aperture in the bottom plate 14 of the head casing.

A locking means for the cords 32—33 is provided in the form of a locking cam 40, pivoted at 41 to the inner side plate 12 of the head casing 10 adjacent to the right pulley 37. This locking cam has a proportionately increasing radius in the counterclockwise direction. As the elevating cords 32—33 are pulled vertically downwardly to elevate the slats 19 and the bottom rail 20, the locking cam 40 will be swung in the counter-clockwise direction, the cords passing freely between the pulley 37 and the locking cam. When it is desired to set the slats 19 in a given position, the elevating cords 32—33 are swung to the right (Fig. 1), and slight downward movement of the slats and consequent reverse movement of the cords will cause the latter to pick up the locking cam 40 and the cords will become wedged between the pulley 37 and the locking cam.

The sectional tilting cords of the present in-

vention comprise two cords 42 and 43. These cords likewise pass downwardly through the same apertures 15—15 in the bottom plate 14 of the head casing as the ladder tapes 21—21 and the elevating cords 32—33, and are positioned adjacent to the inner sides of the ladder tapes 21—21, the cord 42 extending along the left ladder tape (Fig. 1), and the cord 43 along the right ladder tape. At their lower ends, the cords 42 and 43 are attached to the respective ladder tapes 21—21. This attachment may be made in any one of several ways. Knots may be formed in the lower ends of the cords and the cords passed through eyelets, loops, or rings attached to the ladder tapes 21 by stitching. Preferably the attachment is by fittings 44, which may be readily attached and removed so that the ratio of the numbers of slats in the upper and lower sections of the blind may be changed at any time. At spaced intervals along the upper sections of the ladder tapes 21—21, there are secured to the tapes guide members 45 for the cords 42—43. The guide members 45 may be loops stitched to the ladder tapes or eyelets or rings of metal or plastic composition material, also stitched to the ladder tapes.

The upper ends of the cords 42 and 43 are each attached to the top plate 11 of the head casing 10 as indicated at 46. Prior to their point of attachment, the cords 42 and 43 are passed over pulleys 47—47. The pulleys are carried on an actuating bar 48 as by arms 49—49, of which one is shown, fixed to the bar 48. The bar 48 may be considered to have a generally triangular cross-section, as shown in Figs. 2 to 5, inclusive, and one apex of the triangle may be considered the arms 49 carrying the pulleys 47. A second apex of the triangle are the pivot members 50—50 which pivotally support the bar on the top plate 11. The third apex of the triangle is the eye 51 which carries a draw cord 52 at its lower end at a suitable button 53 for retaining the lower slats at any suitable adjustable position. Obviously, by proportioning the triangular cross-section of the actuating bar in a suitable manner a great amount of lift may be imparted to the cords 42 and 43 for a relatively small motion of cord 52.

In Figs. 6 and 7 there is shown a modified form of operating means for the sectional tilting cords 42—43. A lever in the form of a hinged plate 54 is attached to the top plate 11 of the head casing 10 by hinges 55—55. The sectional tilting cords 42—43 are attached to the outer edge of the plate 54 at 56—57, respectively. A crank or arm 58 is attached by bolts or screws (not shown) to the hinged plate 54 near the outer edge of the latter and at approximately the center of same longitudinally. A cord 59 is secured in a suitable eyelet in the outer end of the arm 58 and depends downwardly.

The operation of the Venetian blind of the present invention is as follows: As previously stated, the main tilting cord 30 may be pulled to rotate the pulley 29, shaft 28, worm gear 27, worm wheel 26, shaft 24, and drums 23—23 to raise the inner ladder tape 21 and lower the outer ladder tape thus tilting the slats 19 from the open position of Fig. 1 to the closed position; conversely, the main tilting cord 31 may be pulled to rotate the pulley 29, shaft 28, worm gear 27, worm wheel 26, shaft 24, and drums 23—23 in the reverse direction to lower the inner ladder tape 21 and raise the outer ladder tape and thereby tilt the slats 19 back from the closed position to

the open position of Fig. 1. It has been pointed out above that no braking or locking means is necessary for the pulley 29 or associated rotatable parts in order to hold the slats 19 in the desired angular position if the pitch of the threads on the worm shell 26 and the worm gear 27 is properly selected.

Likewise, the elevating cords 32-33 may be operated to raise all of the slats 19 and the bottom rail 20, the bottom rail first moving against the lowermost slat 19 and that slat against the next, etc., and the ladder tapes 21-21 collapsing in well known accordion fashion. As long as the cords 32-33 are pulled downward vertically or released for upward movement vertically, as the case may be, they will slide past the locking cam 40. However if the cords are swung to the right (Figs. 1 and 3), they will pick up the locking cam and become wedged between the locking cam and the right pulley 31.

Assuming that the blind is in fully extended position and that the slats are tilted to the horizontal or open position, as shown in Fig. 1, and it is desired to tilt the slats in the lower section of the blind to closed position, the draw cord 52 is pulled a distance sufficient to close the lower slats. This through the actuating bar 48 lifts the cords 42-43 and the slats below the fittings 44-44, where the cords are attached to the ladder tapes 21-21, are tilted through an angle the half cord of which is equal to the amount of lift of the cords 42-43. This action results in all of the slats in the section below the fittings 44-44 being tilted and the bottom rail 20 being likewise tilted, while the slats in the upper section above these fittings remain in their horizontal or open position, as shown in Fig. 3. It is therefore obvious that by the use of the invention the slats in the lower section of the blind may be shifted to the desired closed position while the slats in the upper section remain in horizontal or open position, thus permitting unobstructed ventilation and admission of light over this section of the window.

If now it be desired to shift the slats 19 in the upper section of the blind to closed position while allowing those in the lower section to remain in open position, the main tilting cords 30-31 are first operated to shift all of the slats to the closed position. Then, by pulling on the sectional tilting cords 42-43 the slats in the lower section of the blind, below the fittings 44-44, may be shifted to horizontal or open position, while those in the upper section remain in the closed position, as shown in Fig. 4. This result is accomplished by pulling on the sectional tilting cords 42-43, through the bar 48 and cord 52, which causes the ladder tapes 21-21 to raise the inner edges of the slats in the lower section of the blind from their fully closed position to the horizontal or open position. The upward movement of the sectional tilting cords 42-43 results in a crimping of the ladder tapes 21-21 at and above the fittings 44-44 while the cords 42-43 slide through the guides 45 on the ladder tapes 21-21.

While there is here shown and described a certain preferred embodiment of the invention, many other and varied forms and uses will present themselves to those versed in the art without departing from the spirit of the invention, and the invention, therefore, is not limited either in structure or in use except as indicated by the terms and scope of the appended claims.

What is claimed as new and desired to be secured by Letters Patent of the United States is:

1. In a Venetian blind, a support, a plurality of vertically spaced slats, ladder tapes dependent from said support and supporting said slats, tilting means for all of the slats, and auxiliary tilting cord means for a section of said slats, said auxiliary tilting means comprising cords attached to the ladder tapes, means for operating said auxiliary cords comprising a lever mounted longitudinally on said support, and means on said lever member for operating said auxiliary cords.

2. In a Venetian blind, a support, a plurality of vertically spaced slats, ladder tapes dependent from said support and supporting said slats, tilting means for all of the slats, and auxiliary tilting cord means for a section of said slats, said auxiliary tilting means comprising cords attached to the ladder tapes, means for operating said auxiliary cords comprising the lever pivotally mounted longitudinally on said support, said lever having a generally triangular cross section, and means attached to one of the apexes of the triangle for operating the auxiliary cords.

3. In a Venetian blind, a support, a plurality of vertically spaced slats, ladder tapes dependent from said support and supporting said slats, tilting means for all of the slats, and auxiliary tilting cord means for a section of said slats, said auxiliary tilting means comprising cords attached to the ladder tapes, means for operating said auxiliary cords comprising a lever mounted longitudinally on said support, said lever having a generally triangular cross section, pivot means attached to said support and to one of the apexes of the triangle, and means attached to another apex of the triangle for operating said lever and auxiliary cords.

4. In a Venetian blind, a support, a plurality of vertically spaced slats, ladder tapes dependent from said support and supporting said slats, tilting means for all of the slats, and auxiliary tilting cord means for a section of said slats, said auxiliary tilting means comprising cords attached to the ladder tapes, means for operating said auxiliary cords comprising a lever mounted longitudinally on said support and having a generally triangular cross section, pivot means mounted on said support and attached to one of the apexes of the triangle, fastening means for said auxiliary cords attached to another apex of the triangle and operating means for the lever and the auxiliary cords attached to the third apex of the triangle.

5. In a Venetian blind, a support, a plurality of vertically spaced slats, ladder tapes dependent from said support and supporting said slats, tilting means for all of the slats, and auxiliary tilting cord means for a section of said slats, said auxiliary tilting means comprising cords attached to the ladder tapes, means for operating said auxiliary cords comprising a lever hinged at one of its sides to said support, means on said lever for operating said auxiliary cords, and a bracket extending from said lever and attached to an actuating cord for operating the lever and auxiliary cords.
